(57) **CLAIM**

The ornamental design for a fenestration glass article, as shown and described.

DESCRIPTION

FIG. 1 is a perspective view showing a fragmented corner of a fenestration glass article;

FIG. 2 is a front elevational view of the embodiment of FIG. 1;

FIG. 3 is a side elevational view of the embodiment of FIG. 1;

FIG. 4 is a front fragmented corner elevation view of a fenestration glass article;

FIG. 5 is a side elevational view of the glass panel in FIG. 4;

FIG. 6 is a front fragmentary view of a corner of a rectangular glass panel depicting a third embodiment of our fenestration product invention;

FIG. 7 is a side elevational view of the glass panel of FIG. 6;

FIG. 8 is a front fragmentary view of a corner of a rectangular glass panel depicting a fourth embodiment of our fenestration product invention;

FIG. 9 is a side elevational view of the glass panel of FIG. 8;

FIG. 10 is a front fragmentary view of a corner of a rectangular glass panel depicting a fifth embodiment of our fenestration product invention;

FIG. 11 is a side elevational view of the glass panel of FIG. 10;

FIG. 12 is a front fragmentary view of a corner of a rectangular glass panel depicting a sixth embodiment of our fenestration product invention; and,

FIG. 13 is a side elevational view of the glass panel of FIG. 12.

The broken lines are for illustrative purposes only and form no part of the claimed design.
